UNITED STATES PATENT OFFICE.

FRANK C. LUNDBERG, OF CHICAGO, ILLINOIS, ASSIGNOR TO LEVITAN MANUFACTURING COMPANY, OF CHICAGO, ILLINOIS, A CORPORATION OF ILLINOIS.

DRAPERY-SUPPORTING MEANS.

Application filed October 14, 1922. Serial No. 594,483.

To all whom it may concern:

Be it known that I, FRANK C. LUNDBERG, a citizen of the United States, residing at Chicago, in the county of Cook and State 5 of Illinois, have invented a new and useful Improvement in Drapery-Supporting Means, of which the following is a specification.

My invention relates more particularly 10 to drapery supporting means of the type employing brackets which are secured at opposite sides of the opening, such as a window opening, to which the drapery, such as curtains, portières, or the like, are to be applied, and bars, commonly formed of telescoped sections which extend crosswise of 15 the opening and are connected at their ends, which extend at angles to the body portion of the bar, with the brackets through the 20 medium of which these bars are supported.

My primary object is to provide novel, 25 simple and inexpensive means for the purpose stated, which may be readily installed in place and will operate to effectually support the curtains, or other hangings applied thereto, and which, in accordance with the preferred embodiment of my invention, will be sustained in such a manner as to prevent 30 accidental disengagement of the rod portion from the brackets, as for example, under the action of wind blowing against the curtains.

Referring to the accompanying drawings:—

Figure 1 is a plan sectional view of a 35 window frame with my improved drapery supporting means, of a form adapting it to support curtains and overdrapes, applied to position on the window frame. Figure 2 is an enlarged broken section taken at the 40 line 2 on Fig. 1 and viewed in the direction of the arrow, a portion of the bar being broken away. Figure 3 is a section taken at the line 3—3 on Fig. 2 and viewed in the direction of the arrows. Figure 4 is a view 45 like Fig. 2 of another form in which my invention may be provided. Figure 5 is a view in elevation of still another form in which the invention may be provided. Fig. 6 is a view generally like Fig. 4 of still another modification of the invention; and Figure 7, a section taken at the line 7—7 on Fig. 6 and viewed in the direction of the arrows.

As a preface to the following description,

it may be stated that the invention is shown 55 in the drawings as embodied in a structure of the type hereinbefore referred to and comprising a pair of cross rods 8 and 9, which extend generally in parallel relation across the opening to which the draperies 60 are to be applied, this opening, and which may be a window opening, being represented at 10, the rod 8 being located between the rod 9 and the window opening. These rods, which are provided at their ends with 65 the angularly disposed portions 11 and 12, respectively, are shown as each formed of telescoping sections 13 and 14, the cross sectional shape of these rod sections being that represented. The rods 8 and 9 cooperate 70 with brackets represented at 15, which are secured to the inner surfaces of the frame defining the opening 10, these brackets serving to support the rods 8 and 9 in the position shown.

In accordance with the illustration in 75 Figs. 2 and 3, each angularly disposed end of the bars, is provided with a strap 16 shown as, and by preference, struck up from the vertical side wall 17 of the bar to 80 extend intermediate the upper and lower edges of the bar, this strap extending transversely of the median line of the bar, as shown. The brackets 15, which are shown 85 of the double type, for cooperation with the two rods 8 and 9, are each formed of a plate portion 18 at which they fit flatwise against the window casing, being secured thereto, as by screws which extend through the openings 19 and into the frame, and ears 90 20 extending forwardly therefrom at right angles to the plate 18. The ears 20 are preferably shaped as shown in Fig. 2 and afford the upwardly opening recesses 21, the opposite walls 22 of which are preferably 95 vertical, as shown.

The rods 8 and 9 are assembled with the brackets 18 by engaging the ears 20 with the straps 16 to cause the parts to become positioned as shown in Fig. 2, wherein the 100 upper portions of the straps 16 extend into the recesses 21 of the ears 20 and the ends of the rods adjacent the brackets 18 bear preferably throughout their extent, against the outer faces of the plates 18, the several 105 parts being so arranged, as shown, that the straps 16 will fit fairly snugly between the side walls 22 of the recesses 21, whereby

rocking of the rods on the brackets either up or down, will be prevented, thereby eliminating the possibility of the rods becoming displaced, as for example, under the action of wind blowing against the draperies. It will be understood that in the assembling of these parts, the ears will be inserted through the straps 16 and the parts relatively rocked to carry the recesses 21 into registration with these straps, whereupon the parts are moved relatively at right angles to each other to seat the straps in the recesses 21.

It will be noted that the brackets may be used interchangeably at the sides of the window casing and it is immaterial which edge of the rods is uppermost.

In the arrangement shown in Fig. 4 the straps shown at 23, and corresponding with the straps 16 of the preceding figures, instead of extending transversely of the median line of the rods, extend in an inclined direction upwardly and toward the window frame. The ears of the brackets co-operating with the rods of this figure and represented at 24 are preferably of the shape shown to provide a hook-shaped portion 25 which extends through the strap 23, the upper surface of the hook 25 being preferably provided with a projection 26 which aids in stably holding the rod in position on the brackets, the hooks slightly flexing in the operation of assembling the parts.

The arrangement shown in Fig. 5 involves the provision of two parallel straps 27 provided on the drapery rod and corresponding with the straps 16, the bracket of this construction involving the base plate 28 corresponding with the plate 18 of Fig. 2 and an ear 29 corresponding with the ear 20, the ear 29 being slotted inwardly from its outer extremity, as represented at 30, to provide two spaced apart legs 31 having outwardly directed surfaces 32. The curtain rod and bracket are assembled by slipping the rod at its strap portions 27 over the ear 29 to the position shown in Fig. 5, the legs 31 flexing toward each other in this operation, and in the final positioning of the parts as shown, swinging outwardly to overlap at

their surfaces 32, the end portions of the strap 27 farthest from the bracket 28.

The construction shown in Figs. 6 and 7 involves, in place of the strap portion of the preceding figures, a headed rivet, represented at 33, which is mounted in the side portion of the drapery rod, between the upper and lower edges thereof, in a position to engage with the ear 24 of the bracket, this bracket being the same as that shown in Fig. 4, as represented in Fig. 6. While I have illustrated and described certain particular constructions embodying my invention, I do not wish to be understood as intending to limit it thereto, as the same may be otherwise variously modified and altered without departing from the spirit and scope of my invention.

What I claim as new, and desire to secure by Letters Patent, is:

1. A curtain rod provided on its side wall, adjacent an end thereof, with a strap located between its upper and lower edges and struck from the body of the rod and forming a loop for engagement with a supporting bracket.

2. A curtain rod provided on its side wall, adjacent an end thereof, with a strap extending transversely of said rod and located between its upper and lower edges and forming a loop for engagement with a supporting bracket.

3. A rod and bracket structure comprising a rod and a bracket provided with inter-engaging releasable parts the inter-engaging part on said rod being a strap located between the upper and lower edges of the rod and struck from the body of the rod to form a loop for receiving the said inter-engaging part of said bracket.

4. A rod and bracket structure comprising a rod and a bracket provided with inter-engaging releasable parts the inter-engaging part on said rod being a strap extending transversely of said rod and located between the upper and lower edges of the rod and forming a loop for receiving the said inter-engaging part of said bracket.

FRANK C. LUNDBERG.
